UNITED STATES PATENT OFFICE.

ANDREW B. HENDRYX, OF NEW HAVEN, CONNECTICUT.

DESIGN FOR A FISHING-REEL.

SPECIFICATION forming part of Design No. 21,546, dated May 17, 1892.

Application filed January 18, 1892. Serial No. 418,505. Term of patent 14 years.

To all whom it may concern:

Be it known that I, ANDREW B. HENDRYX, of New Haven, in the county of New Haven and State of Connecticut, have invented a new 5 Design for the Ornamentation of Fishing-Reels; and I do hereby declare the following, when taken in connection with accompanying drawing and the letters of reference marked thereon, to be a full, clear, and exact description 10 of the same, and which said drawing constitutes part of this specification, and represents a perspective view.

This invention relates to a design for the ornamentation of the heads of fishing-reels; 15 and it consists in the ornamentation as shown in the accompanying illustration. On the flat outer face of the cylindrical head is the representation of a cord forming on the said surface of the head a ring *a*, concentric with the periphery thereof, and inside this ring concentric segments *b b* are represented. The

handle *c* is located within the said ring *a* and is eccentric to the center of the head. The opposite end of the reel has a circular plate *d*, corresponding in diameter to the said head, 25 with which it is represented as being connected by rods *e e* and a central drum *f*.

The leading feature of my design is the representation upon the flat outer face of the circular head of a fishing-reel, of one or more 30 cords concentric with the periphery of the said head.

I claim—

The design for the ornamentation of fishing-reels, as herein shown and described. 35

In testimony whereof I have signed this specification in the presence of two subscribing witnesses.

ANDREW B. HENDRYX.
